UNITED STATES PATENT OFFICE

143,425

DESIGN FOR A BOOT OR SIMILAR ARTICLE

Sanford J. Jarrell, Norfolk, Va.

Application April 26, 1945, Serial No. 119,227

Term of patent 14 years

(Cl. D7—4)

To all whom it may concern:

Be it known that I, Sanford J. Jarrell, a citizen of the United States, residing in the city of Norfolk, State of Virginia, have invented a new, original, and ornamental Design for a Boot or Similar Article, of which the following is a specification, reference being had to the accompanying drawing, forming part thereof.

Figure 2 is a rear elevational view showing the closure means in the rear of the boot or similar article.

I claim:

The ornamental design for a boot or similar article, substantially as shown.

SANFORD J. JARRELL.
